UNITED STATES PATENT OFFICE.

JOHN TAYLOR, OF TROY, NEW YORK.

ELECTRIC-CAR TRUCK.

SPECIFICATION forming part of Letters Patent No. 561,530, dated June 2, 1896.

Application filed April 29, 1895. Serial No. 547,526. (No model.)

To all whom it may concern:

Be it known that I, JOHN TAYLOR, of Troy, in the county of Rensselaer and State of New York, have invented certain new and useful 5 Improvements in Electric-Car Trucks; and I do hereby declare that the following is a full, clear, and exact description thereof, reference being had to the accompanying drawings, and to the letters of reference marked thereon, 10 which form part of this specification.

This invention is an improvement upon the car-trucks for electric railways shown and described in my Patent No. 507,050, dated October 17, 1893; and it consists in the novel 15 construction of the pedestals and certain other parts of the truck hereinafter described and claimed.

Referring to the drawings, Figure 1 is a side elevation of the truck. Fig. 2 is a detail 20 end view thereof; Fig. 3, a detail transverse vertical section on line 3 3, Fig. 1. Fig. 4 is an enlarged vertical longitudinal section through a pedestal, journal-box, and springs. Fig. 5 is a bottom view of the pedestals. Figs. 25 6 and 7 are details of one of the combined strut-and-clevis castings. Figs. 8 and 9 are detail views of the bracket-casting.

A designates the top frame of the truck, to which the pedestals are attached. Each pedestal 30 substantially consists of a pair of vertical opposite tubes B B, depending from a top plate B', which closes their upper ends, their lower ends being open. The tubes are slotted at their inner sides, as at B², for the entrance 35 of the lateral wings C' of the journal-box C, which fits between the tubes and is free to move vertically therebetween. The wings C' are provided with seats C² for coiled springs D, which are inserted in the tubes between 40 the wings and the top plate B', thereby supporting the pedestal upon the journal-box, as shown. The object of this construction is to enable long coil-springs to be used and yet reduce the height of frame by placing the 45 springs beside instead of on top of the journal-box. This idea, however, is not new with me, nor is the journal-box *per se*. The pedestals, however, are entirely novel, in my opinion. It will be observed that the tubes 50 inclose and protect the springs, and they (the tubes) may be closed on all sides, except for

slots B², if desired; or side openings B³ may be made in the tubes for reducing weight thereof. The tubes may be stiffened at their upper ends by lateral wings or bracket-flanges 55 b, connecting them to plate B', and after the journal-box and springs are in place a yoke-bar b' is bolted to the lower ends of tubes, as shown, both uniting them more securely and confining the boxes therebetween. Obviously the boxes and springs are inserted in pedestals by pushing them up from below or by slipping the pedestals over the springs and boxes.

The pedestals on same side of truck are 60 connected by the parallel bars E E substantially as in my aforesaid patent, and the frame intermediate the adjoining pedestals is trussed by a bar H, between which and frame A is a casting F. The truss-bars are 70 connected by a transverse motor-sustaining bar h, and at each side of the truss-bar are elliptical springs G G, carrying the bolster g.

The parts E, F, G, H, and g are constructed and arranged substantially as described in 75 my patent aforesaid; but the bar h is set edge-wise and its ends h' given a half-twist, so that they lie broadside upon the truss-bars, as shown. By thus constructing and arranging the bar h I obtain more room for the motors 80 and a support for rear end thereof and materially reduce the vibrations occurring in flat motor-bars when the cars are running at a high rate of speed.

I is a bracket-casting supported on bars E E, 85 directly under the ends h' of bars H and beneath the spring. This casting has upper and lower flanges I', embracing bars E E, and above said bars has wings I², which extend up opposite sides of truss-bar H and are bolted 90 to the ends h' of the bar h. Castings I stand at right angles to castings F and the bars E H and assist in supporting the weight of the springs, bolster, and motor-bar. The casting I is held in place by a long bolt i, which trans-fixes the frame A, casting F, and bars H h, 95 as shown.

The end portions of frame A are trussed by rods J, which pass under castings K, attached to the frame and formed with strut 100 portions K', that stand between the rod J and frame, and with inwardly-projecting clevis

portions K², to which the ends of motor-sus-
taining bars or strips L are attached, as in-
dicated in the drawings.

Having thus described my invention, what

5 I therefore claim as new, and desire to secure
by Letters Patent thereon, is—

1. The herein-described bracket-casting I,
having upper and lower flanges I', lateral
wings I², and a central bolt-opening, sub-
stantially as and for the purpose described.

2. In a truck-frame the combination of the
top frame, pedestals, and connecting-bars,
the truss-bars, the motor-bar h, set edgewise
but twisted near its ends, substantially as
15 described, the elliptic springs and bolster,
and the bracket-castings I, I, having flanges
I' and wings I², all substantially as and for
the purpose set forth.

3. The combination in a truck, of the top
20 frame, the truss-rods, and castings K, having
strut portions K', and bifurcated clevis K²,
at each end thereof; the pedestals the bars
E, E, truss-bar H, the motor-bar h set edge-

wise but twisted near its ends, and the cast-
ings I, I, having flanges I', and wings I², all 25
constructed and arranged substantially as
described.

4. The combination in a truck, of the top
frame, the truss-rods, and castings K inter-
posed between the rods and frame at each 30
end of the truck, the pedestals composed of
tubes B, B, and top plate B'; the yoke-bars
b; the bars E, E, truss-bar H motor-bar h,
and castings I, I, interposed between bars E
and II, with the axle-boxes having lateral 35
wings entering the tubes B, B, and the springs
confined in said tubes, and supported on said
wings, all constructed and arranged substan-
tially as and for the purpose set forth.

In testimony that I claim the foregoing as 40
my own I affix my signature in presence of
two witnesses.

JOHN TAYLOR.
